UNITED STATES PATENT OFFICE.

WALLACE R. BROWN, OF OLEAN, NEW YORK.

TOOL.

1,226,636.

Specification of Letters Patent. Patented May 22, 1917.

Application filed May 20, 1916. Serial No. 98,751.

To all whom it may concern:

Be it known that I, WALLACE R. BROWN, a citizen of the United States, and a resident of Olean, in the county of Cattaraugus 5 and State of New York, have invented a new and Improved Tool, of which the following is a full, clear, and exact description.

Among the principal objects which the 10 present invention has in view are: to provide a pocket knife, the handle of which is adapted for use as a blade-holder, and to provide a series of blades adapted for temporary mounting in said handle; to guide 15 the blades when being applied to said handle; to provide means for holding a blade in said handle; and to provide means for readily disengaging a blade from said handle.

20

Drawings.

Figure 1 is a side elevation of a tool constructed and arranged for service in accordance with the present invention;

25 Fig. 2 is a similar view, the side plate of the handle being removed, the view being taken as on the line 2—2 in Fig. 4, and showing a detachable blade disposed as in service:

30 Fig. 3 is a similar view showing the blade as partially withdrawn from its service position;

Fig. 4 is a cross section on an enlarged scale, the section being taken as on the line 35 4—4 in Fig. 2;

Fig. 5 is a detail view showing an alternative blade supportable from the handle.

Description.

40 As shown in the drawings, the holder for tool blades, such as the screw-driver 10 and file 11, is the handle of the knife blade 12, which is permanently incorporated with the said handle to form a folding or 45 pocket-knife. The blade 12 is pivotally mounted between the reinforced ends 13 of the handle plates 14. The pivot 15, which holds the blade 12, is headed on the outer side of the reinforcing ends 13, as is usual 50 in the construction of knives of the general character here indicated.

At the opposite end of the handle, a spacing pin 16 is provided. The pin 24 serves normally as a rest for the free end 17 of a locking spring 18. The spring 18 is held 55 between the handle plates by an anchor pin

19. The extremity of the end 17 projects beyond the pin 16 to form a guide rest for the wedge shank 20 with which each of the blades, such as 10 and 11, is provided.

When the separable blades, such as 10 and 11, are removed from the handle, the knife blade 12 may be disposed in closed or open position, as desired, and is so held by the end 21 of the spring 18 in the usual manner. A like office is performed for the blades 10 and 11, by the end 17 of the spring 18, which holds the shank 20 in firm contact with the pin 16, and holds the nick 22 with which the extension 20 is provided, in 60 engagement with said pin.

When the nick 22 is thus engaged by the pin 16, an abutment 23 with which each of the blades is provided, rests firmly against the extremity of the end 17, as best shown 65 in Fig. 2 of the drawings. The back edge 25 of the shank 20, when the blades are held in service in the handle, rests firmly on the inner surface of the end 17, which corrects any tendency of the blade to rock on the 70 pin 16.

The shank 20 has an offset 26 extending from the edge of the blade opposite to that in which is formed the abutment 23. The offset 26, as shown best in Fig. 2 of the 75 drawings, rests in service between the reinforced ends 13 to assist in resisting the torsional strain on the screw-driver 10 and file 11, or other tool blade, when used.

Operation.

When provided with a construction such as described and as shown in the accompanying drawings, any one of the tool blades having a shank 20 provided with a nick 22 and an abutment 23, is inserted in the handle having the plates 14, by resting the extremity of the shank 20 on the extremity of the end 17 where the same protrudes beyond the pin 16. The extremity of the shank 20 is then inserted between the pin 16 and end 17, so that the blade on being pressed into the handle, forces the end 17 of the spring 18 backward until the nick 22 registers with the pin 16. The action of 100 the spring then forces the nick to engage the pin to lock the blade in the handle. It will be found that at the moment of engagement by the nick 22 of the pin 16, the extremity of the end 17 engages the abutment 105 23. The blade is thereafter held in the handle against accidental rocking.

If it is desired to remove the blade from its service position, as shown in Figs. 1 and 2, the blade is forced in the direction indicated by the arrow in Fig. 2 while the handle is held immovable. The pressure thus applied forces the end 17 backward, the spring 18 yielding to this end. As soon as the nick 22 of the extension 20 clears the pin 16, the blade may be drawn from between the end 17 and pin 16. The abutment 23 assists in this action, forming, as it does, a rocking joint on the extremity of the end 17, which rocks the nick 22 forward as the end of the blade is depressed in the manner indicated. Thus by forcing the blade backward in the direction shown by the arrow in Fig. 2, no further action is required to free the blade from engagement with the pin 16 and the handle of which the said pin forms a structural part.

Claim.

A tool comprising a handle having paral-

lel sides spaced apart for forming a blade-holding recess; an engaging member disposed in said recess adjacent the forward end thereof; a removable blade having a wedge-shaped shank, said shank having formed at one edge thereof a holding nick for engaging said member, the other edge of said shank being provided with an abutment for rocking said blade out of engagement with said member; and means mounted in said handle for holding said shank in engagement with said member, said means embodying a spring adapted to engage the inclined edge of said shank and to yield to permit the introduction of said shank between said member and said spring and the withdrawal of said shank from engagement with said member, said spring engaging said abutment to form a movable fulcrum whereon said blade may rock for removing said nick from said member.
